UNITED STATES PATENT OFFICE.

LOUIS E. CUMMINGS, OF ST. JOSEPH, MISSOURI, ASSIGNOR TO THOMAS W. STAMEY AND JOHN W. STAMEY, OF ST. JOSEPH, MISSOURI.

ROTARY ENGINE.

No. 861,164.

Specification of Letters Patent.

Patented July 23, 1907.

Application filed September 1, 1906. Serial No. 332,960.

To all whom it may concern:

Be it known that I, LOUIS E. CUMMINGS, a citizen of the United States, residing at St. Joseph, in the county of Buchanan and State of Missouri, have invented certain new and useful Improvements in Rotary Steam-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of my invention is to provide a rotary steam engine that will occupy an unusually limited space, that may be attached to a shaft in any position; that is extremely simple in construction and of low cost; in which there is no back pressure of steam and that will produce a maximum of power from a minimum of fuel.

I attain my object by the mechanism illustrated in the accompanying drawings in which,—

Figure 1 is a longitudinal section of the engine; Fig. 2 is a detail of a steam valve and Fig. 3 a detail showing a side elevation of the valve shown in Fig. 2; Fig. 4 is a cross section of the engine; Fig. 5 is a detail of a steam paddle and spring and Fig. 6 a detail side section of said paddle and spring; Fig. 7 is a side sectional elevation of the engine showing the exhaust and steam valves in operation, the upper half of the figure showing the live steam side; the lower part showing the exhaust or waste steam side; Fig. 8 is a detail cross section of an endless partition and the parts therein, shown at line $x-x$ of Fig. 9, and Fig. 9 is a detail longitudinal section showing the construction of the endless partition.

Similar letters refer to similar parts in the several views.

A represents a support for the engine and B a jacket for the same.

C is the steam chest and C' the shell thereof. C² is a dead air space between said jacket and shell to keep the cold air from said chest and prevent the steam being chilled.

D is the shaft and E E— the parts of a revoluble cylinder carried by said shaft.

H is a drive wheel, H' a belt pulley, I a steam pipe adapted to form connection between any suitable boiler and the cylinder and J J— are ports for the admission of steam from said pipe into said steam chest.

L L are exhaust ports, L' an exhaust chamber, and L² an exhaust pipe.

M is a partition between said exhaust chamber and the steam chest. M' is a side plate fitting against said steam chest.

O O— are paddles operating in guideways O' O'—. 55
m m— are guides for guiding paddles O O past ports m' m'— in endless partition M.

P P are springs at the inner ends of said paddles which also operate in said guideways and P' P' are exhaust valves. The steam entering ports J J presses 60 against these paddles by its force revolving the cylinder after each of said springs has pressed its paddle outward after the paddle has passed an exhaust.

P² P²— are steam valves.

R is a grooved bearing showing how the steam valve 65 opens and closes.

S S— are bearings.

From the foregoing description it will be readily seen that as the steam passes through ports J J into steam chest C and each paddle is revolved beyond an 70 exhaust P', each spring pushes and holds its paddle outward against shell C' and the incoming live steam by its pressure upon the paddles revolves the steam cylinder.

What I claim and desire to secure by Letters Patent 75 is,—

1. In a rotary steam engine the combination with a support, connecting and exhaust pipes, a drive wheel and belt pulley, of a shaft and the revoluble cylinder carried thereon, a shell and a steam chest inclosed therein, a jacket 80 forming a dead air chamber outside said shell, a partition consisting of a plurality of corresponding irregular curves contacting alternately with the shell of said steam chest and the periphery of the revoluble cylinder, ports for the admission of live steam and for the escape of exhaust 85 steam and the exhaust chamber, a plurality of guideways in said revoluble cylinder opening out of the periphery of the same into said steam chest, a plurality of paddles operating in said guideways and the springs at the inner ends thereof adapted to press said paddles outward and 90 keep them in contact with said partition as each paddle passes an exhaust port and receives the live steam, substantially as shown and described.

2. The combination with a steam chest having ports for the supply and exhaust of steam, of a rotary shaft, a revoluble cylinder carried on said shaft, an endless partition consisting of a plurality of irregular curves adapted to contact with interior of the shell of the steam chest and exterior of the periphery of the revoluble cylinder, alternately, a plurality of guideways having their outlets in the periphery of said cylinder, paddles operating in said guideways each adapted to be forced back within said periphery as its guideway is revolved into engagement with an inner curve of the partition, and springs back of said paddles each adapted to force and hold its paddle out into engagement with partition while the guideway is being revolved to the next inner curve of the partition and next exhaust, substantially as set forth and shown.

In testimony whereof, I affix my signature, in presence of two witnesses.

LOUIS E. CUMMINGS.

Witnesses:

N. S. HILLYARD,
WM. B. SNYDER.
